CLAIM

The ornamental design for an enclosure for an optical system, as shown and described.

DESCRIPTION

FIG. 1 is a front perspective view of a second embodiment of an enclosure for an optical system of the present invention;

FIG. 2 is a front elevation view of the invention illustrated in FIG. 1;

FIG. 3 is a rear elevation view of the invention illustrated in FIG. 1;

FIG. 4 is a left side view of the invention illustrated in FIG. 1;

FIG. 5 is a right side view of the invention illustrated in FIG. 1;

FIG. 6 is a top view of the invention illustrated in FIG. 1;

FIG. 7 is a bottom view of the invention illustrated in FIG. 1;

FIG. 8 is a front perspective view of a third embodiment of an enclosure for an optical system of the present invention;

FIG. 9 is a front elevation view of the invention illustrated in FIG. 8;

FIG. 10 is a rear elevation view of the invention illustrated in FIG. 8;

FIG. 11 is a left side view of the invention illustrated in FIG. 8;

FIG. 12 is a right side view of the invention illustrated in FIG. 8;

FIG. 13 is a top view of the invention illustrated in FIG. 8;

and,

FIG. 14 is a bottom view of the invention illustrated in FIG. 8.

The broken lines in the drawings illustrate portions of the enclosure for an optical system and form no part of the claimed design.
